WELL BIT CUTTER MOUNTING

Alfred C. Catland, Alhambra, Calif., assignor to
 Globe Oil Tools Company, Los Nietos, Calif.,
 a corporation of California

Application September 25, 1936, Serial No. 102,527

7 Claims. (CL 255—71)

This invention relates to well drilling tools and relates more particularly to the mountings or bearings for the roller cutters of well bits. A general object of this invention is to provide improved anti-friction bearings for roller cutters that are efficient and long wearing.

Roller rock bits have been employed embodying rollers for rotatably supporting the roller cutters on the pins or shafts of the bits. Such bearings or rollers are only capable of assuming the radial loads or thrusts and it has been the accepted practice to provide thrust washers at the ends of the cutters to assume the end thrusts. Thrust washers even though they be hard or formed of hard material wear very rapidly, particularly where abrasive earth formations are encountered in the wells.

Another object of this invention is to provide an improved anti-friction bearing for the roller cutter of a well bit that embodies a series of anti-friction members that take or assume both the radial and axial thrusts or loads thereby eliminating the necessity for thrust washers.

Another object of this invention is to provide a mounting or bearing for the roller cutter of a well bit that embodies a series of balls arranged between the interior of the cutter and the cutter carrying bushing in a manner to assume both the radial thrusts and the end thrusts imposed on the cutter.

Another object of this invention is to provide a cutter bearing of the character mentioned that provides a series of balls within each end portion of the cutter to transmit the radial thrusts as well as the end thrusts in both directions.

Another object of this invention is to provide an improved cutter supporting bearing of the character mentioned in which the points of contact of the balls with the interior of the cutter and the bearing bushing lie in a plane substantially normal to or at right angles to the principal formation engaging edges of the cutter to effect the most efficient operation of the bearing.

Another object of this invention is to provide an improved bearing means for rotatably supporting the cutter of a bit that is simple and inexpensive and that is easy to assemble.

A further object of this invention is to provide an anti-friction bearing for the roller cutter of a well bit that embodies rollers for assuming or transmitting the radial thrusts and a series of balls acting between the cutter and a bearing bushing for transmitting the principal end thrusts and a portion of the radial thrusts.

The various objects and features of my invn-

tion will be fully understood from the following detailed description of typical preferred forms and applications of my invention, throughout which description reference is made to the accompanying drawings, in which:

Fig. 1 is a side elevation of a well bit embodying the bearings provided by the present invention illustrating the lower portion of the bit in central vertical cross section. Fig. 2 is an enlarged fragmentary detailed sectional view taken as indicated by line 2—2 on Fig. 1. Fig. 3 is a fragmentary vertical detailed sectional view of the lower portion of the bit taken in a plane at right angles to the plane of the sectioning in Fig. 1. Fig. 4 is an enlarged fragmentary detailed sectional view of the bearing for supporting one of the outer cutters. Fig. 5 is an enlarged fragmentary longitudinal sectional view of the bearing means for supporting one of the inner cutters and Fig. 6 is a view similar to Fig. 4 illustrating a slightly modified form of bearing.

The cutter mounting means or bearings provided by the present invention are adapted to be employed for rotatably supporting the roller cutters of various forms of well bits. In the following detailed disclosure I will describe several typical forms of the invention rotatably mounting the cutters of a well bit of the character fully described and claimed in my co-pending application entitled "Roller rock bit", Serial No. 88,989, filed July 6, 1936.

The bit illustrated in the drawings includes a shank or body 10 adapted to be connected with a rotary well drilling string. The body 10 has a tapered threaded socket 11 in its upper end for receiving a pin on the drill collar or other part of the drilling string. Two diametrically opposite legs or wings 12 project downwardly and slightly outwardly from the lower end of the body 10. The wings 12 have flat substantially vertical inner surfaces 13. Flat substantially horizontal shoulders 14 occur on the wings 12 at the lower ends of their inner surfaces 13. The body 10 further includes two opposite legs or wings 15. The wings 15 project downwardly and outwardly from the lower end of the body 10 and are spaced substantially 90° from the wings 12. The wings 15 have flat downwardly and outwardly inclined inner surfaces 16 and flat shoulders 17 on their lower ends.

A cutter carrying shaft or pin 18 extends across the open lower end of the body 10 between the opposite wings 12. The major portions of the pin 18 are inclined upwardly and inwardly toward the central vertical axis of the bit. The

intermediate portion 18^a of the pin 18 is cylindrical and substantially horizontal. Screws 19 are passed through openings in the wings 12 and threaded into openings in the opposite ends 5 of the pin 18 to connect the pin and the wings 12. The heads of the screws 19 may have portions 19^a peened into notches in the outer sides of the wings 12 to prevent unthreading of the screws. The cutter supporting pin 18 has reduced end portions 20 adjacent the inner sides of the wings 12. A central web 21 projects from the lower end of the body 10 and has two downwardly and outwardly projecting wings 22 spaced inwardly from the wings 15. The outer sides 23 10 of the wings 22 are flat and parallel with the surfaces 16 of the wings 15. Flat shoulders 22^a occur on the lower ends of the wings 22. Cutter supporting pins 24 are passed outwardly through openings in the wings 22 and are threaded 15 in openings 25 in the wings 15. The outer end portions of the pins 24 have parts distorted or peened into notches 26 in the outer sides of the wings 15. The heads of the screws 24 may have similar parts distorted into notches 27 in 20 the inner sides of the wings 22. The parts of the screws 24 peened into the notches 26 and 27 positively prevent unthreading of the cutter supporting pins 24 when the tool is in operation. In the event that one peened over portion of a 25 pin 24 may be worn away through contact with the earth formation the other may remain to prevent loss of the pin.

A stud 28 is arranged through a vertical opening 29 in the body web 21. The lower portion of 30 the stud 28 is enlarged and has an opening 30 receiving the intermediate portion 18^a of the pin 18 whereby the stud serves to support the pin between its ends. A connecting pin 31 may be arranged through transverse openings in the stud 28 35 and the portion 18^a of the pin 18. A nut 32 is threaded on the projecting upper end of the stud 28 to retain the stud in position. Fluid discharge members 33 are arranged in spaced openings in the body 10 to discharge the circulation fluid 40 downwardly against the cutters on the pin. The nut 32 may serve to hold the discharge members 33 in position.

The bit further includes two like outer cutters A supported on the pins 24 through the bearings 50 provided by the invention and a set of inner cutters B and C rotatably supported on each inclined portion of the pin 18. The outer cutters A are frusto-conical having peripheral cutting teeth 34 provided with inclined or pitched cutting edges 35. The opposite ends of the cutters A may be flat 55 and normal to the axis of the cutters. The ends and the interiors of the cutters A are formed to operate with the bearing means of the invention as will be hereinafter described.

The inner cutters B are cylindrical roller cutters provided with peripheral cutting teeth 36. The opposite ends of the cutters B may be flat and the inner ends of the cutters may be recessed or relieved to receive adjacent parts of the web 21. 60 The cutters B may be rotatably supported on the pin 18 by series of anti-friction rollers 37. Suitable washers 38 may space the inner ends of the rollers 37 from the adjacent faces of the web 21. The inner cutters C which surround the pin 18 65 between the cutters B and the wings 12 are frusto-conical cutters provided with peripheral teeth 39 having pitched or inclined cutting edges 40. The cutters C are arranged with their large ends facing outwardly. The inner ends of the cutters C may be flat and normal to the axes of 70

the cutters. The interiors of the cutters C and their outer ends are shaped or formed to cooperate with the bearing means provided by the invention as will be hereinafter described.

The bearing means provided by the present invention and illustrated in Figs. 1, 2 and 4 of the drawings for rotatably supporting each outer cutter A includes, generally, annular surfaces or races 41 and 42 on the interior of the cutter, a sectional bushing 43 on the cutter supporting pin 24 10 and series of balls 44 cooperating with the races 41 and 42 and the bushing 43.

The surfaces or races 41 and 42 are provided on the interior of the cutter A to partially receive and to cooperate with the balls 44. The races 41 and 42 are alike in shape and may be of the same diameter. In accordance with the invention the races 41 and 42 are spherically concaved to have proper cooperation with the balls 44. The races 41 and 42 are oppositely disposed, that is, the race 20 41 faces toward the adjacent wing 15, while the race 42 faces toward the adjacent wing 22. The races 41 and 42 on the interior of the cutter A are spaced axially by an annular ridge 45 on the interior of the cutter A. The cutter A may have 25 cylindrical internal surfaces 46 extending inwardly from its ends to merge with the races 41 and 42. The surfaces or races 41 and 42 may extend or curve inwardly to the internal or peripheral surface of the ridge 45. Annular sockets or 30 recesses 47 are provided in the opposite ends of the cutter A. The above described ridge 45 is substantially equally spaced between the opposite ends of the cutter A so that the races 41 and 42 are substantially equally spaced from the central transverse plane of the cutter.

The bearing bushing 43 is provided on the pin 24 to be engaged by the series of balls 44. The bushing 43 is preferably sectional to facilitate the assembly of the balls 44 within the cutter A. In 40 practice the bushing 43 includes two similar or like sections 48. The sections 48 are tubular and surround the pin 24. The pushing sections 48 are complementary and oppositely disposed to have their inner ends in abutment as illustrated. An 45 annular flange 49 is provided on the outer end of each bushing section 48. The outer side of the flange 49 of the outermost section 48 cooperates with the inner surface 16 of the adjacent wing 15 while the outer surface of the flange 49 on the other bushing section 48 cooperates with the surface 23 of the adjacent wing 22. The peripheral portions of the flanges 49 are received or partially received in the recesses 47 as illustrated. The flange 49 of the outer section 48 has a projecting 50 tongue 50 cooperating with the shoulder 17 to prevent rotation of that section. The flange 49 of the inner section 48 has a similar tongue 51 cooperating with the shoulder 22^a to prevent rotation of that section. The flanges 49 fitting the recesses 47 close the outer ends of the ball carrying space within the cutter A.

Each bushing section 48 is provided with a spherically concaved surface or race 52. The race 65 52 of the outer bushing section 48 opposes the race 41 while the race 52 of the inner section 48 opposes the race 42. The races 52 occur in the corners between the peripheries of the bushing sections 48 and the inner sides 53 of the flanges 49. The peripheries of the sections 48 and the inner surfaces 53 of the flanges 48 preferably merge with the races 52, as illustrated. The peripheries of the bushing sections 48 may be cylindrical and the inner surfaces 53 of the flanges 48 70 75

may be normal to the longitudinal axes of the sections 48.

The series of balls 44 are arranged within the cutter A to cooperate with the sets or pairs of opposing races 41 and 52 and 42 and 52. The balls 44 are operable to transmit the radial thrusts and the end thrusts to which the cutter A is subjected and are preferably hard steel balls. The races 41, 42 and 52 are properly curved or formed to have effective engagement with the balls 44. The diameter of the balls 44 is such that the balls form the sole means for rotatably supporting the cutter A on the bushing 43. It is an important feature of the invention that the sets of races 41 and 52 and 42 and 52 are related so that the balls 44 assume the axial thrusts in both directions, as well as the full radial thrusts. This action results from the location and relation of the faces 41 and 42 on the interior of the cutter A and the location of the races 52 in the corner between the peripheries of the sections 48 and the inner surfaces 53 of the flanges 51. While the disposition of the races 41 and 42 and 52 may be varied somewhat and yet attain the desired result it is preferred to provide and locate the races so that a line extending through the central points of contact of a ball 44 with the race 41 and the race 52 is substantially normal to the cutting edge 35 of a tooth 34 as illustrated in Fig. 4 of the drawings. This particular relationship has been found to be most practical and to provide for the full transmission of the principal axial thrust of the cutter A as well as the radial thrusts with a minimum of friction and wear.

Due to the inclination of the cutter A the heavier or principal end thrusts are imposed on the balls 44 cooperating with the races 41 and 52. The balls 44 cooperating with the races 42 and 52 of course assume the other end thrusts.

Fig. 6 of the drawings illustrates a slightly modified form of bearing for rotatably supporting an inclined roller cutter A'. The cutter A' may be substantially the same as one of the above described cutters A and is provided with two internal races 41^a and 42^a. The races 41^a and 42^a may be substantially the same as the above-described races 41 and 42. The bearing means for rotatably supporting the cutter A' includes two bushing sections 48^a and 48^b similar, generally to the above described bushing sections 48. The bushing sections 48^a and 48^b surround and are supported by a pin 24^a which may be identical with one of the pins 24. The bushing sections 48^a and 48^b are arranged in opposing end to end relation with their inner ends in cooperation. Flanges 49^a corresponding to the flanges 49 are provided on the outer ends of the sections 48^a and 48^b. The section 48^a is provided with a ball race 52^a and the section 48^b is provided with a ball race 52^b. In the structure illustrated in Fig. 6 of the drawings the bushing section 48^a is somewhat larger in effective diameter than the section 48^b so that its race 52^a is larger in diameter than the race 52^b. Annular rows or series of balls 44^a are arranged within the cutter A' to cooperate with the opposing races of the cutter and the bushing sections 48^a and 48^b. The balls 44^a of the two rows or series may be of the same diameter and where the race 52^a is larger in effective diameter than the race 52^b the race 41^a of the cutter is preferably larger in effective diameter than the race 42^a to properly accommodate the balls 44^a. The balls 44^a cooperate with the sets of races 41^a and 52^a and 42^a and 52^b in the same manner as the races

and balls in the above described form of the cutter mounting. Owing to the inclination or pitch of the cutter A' the principal or heavy end thrusts are imposed on the balls 44^a cooperating with the races 41^a and 52^a. Owing to the fact that the races 41^a and 52^a are larger in effective diameter than the races 42^a and 52^b they present larger bearing surfaces and a larger number of balls 44^a may cooperate with them for the dependable transmission of the heavy end thrusts.

The bearing means provided by the present invention for rotatably mounting each inner cutter C on the pin 18 includes rollers 60 rotatably supporting the cutter C on the pin 18 for the transmission of the radial thrusts, a bushing 61 on the pin 18 at the outer end of the cutter C and a series of balls 62 operating between the cutter C and the bushing 61. As the means for supporting the cutters C may be identical I will proceed with a detailed description of one of the bearing or mounting means, it being understood that such description is also applicable to the means for supporting the other cutter C.

The major inner portion of the cutter C is 25 cylindrical and its wall is concentric with the longitudinal axis of the pin 18. An annular or tubular series of rollers 60 surrounds the pin 18 within the inner portion of the cutter C to have 30 rolling cooperation with the pin 18 and the cylindrical interior of the cutter. A suitable thrust washer 63 is interposed between the inner ends of the rollers 60 and the adjacent ends of the rollers 37 and the cutter B. It will be apparent how the bearing rollers 60 assume most of the 35 radial thrusts to which the cutter C is subjected.

An annular recess 64 occurs in the outer end of the cutter C. The recess 64 is deepened or extends into the cutter C to have a spherically concaved ball race 65. The race 65 occurs in 40 what may be termed the corner between a radial wall and an axial wall of the recess 64. The race 65 is spherically concaved to properly cooperate with the series of balls 62.

The bushing 61 is arranged on the reduced end 45 portion 20 of the pin 18 and has an internal shoulder 66 cooperating with the shoulder 67 of the pin 18 which occurs at the inner end of its reduced portion 20. The bushing 61 extends inwardly to have its inner portion surrounding the 50 body of the pin 18 within the cutter C. The inner end of the bushing 61 is adjacent or cooperates with the outer ends of the rollers 60 and thus limits outward movement of the rollers. The bushing 61 is provided with an annular 55 flange 68 whose outer surface cooperates with the surface 13 of the adjacent wing 12. A tongue 69 is provided on the flange 68 to cooperate with the shoulder 14 of the adjacent wing 12 to prevent rotation of the bushing 61. The flange 68 60 is partially received in the recess 64 of the cutter C and serves to close the outer end of the ball receiving space within the cutter. An annular spherically concaved ball race 70 is provided on the bushing 61. The race 70 opposes the race 65 65 of the cutter C. The race 70 occurs in the corner between the inner surface of the flange 68 and the periphery of the bushing 61.

The annular series of balls 62 is arranged in the cutter C to cooperate with the opposing races 65 70 and 70. The races 65 and 70 are related and formed so that the balls 62 cooperating with them dependably transmit the principal end thrusts to which the cutter C is subjected and assume some of the radial thrusts on the cutter. It is to be 75

noted that a line extending through the points of contact of a ball 62 with the races 65 and 70 is substantially perpendicular to the longitudinal axis of the cutter C and the edges of the cutter teeth.

It is believed that the operation of the cutter supporting bearings of the present invention will be readily understood from the foregoing detailed description. The bearings rotatably supporting the outer cutters A involve the two rows of balls 44 which assume all of the end thrusts as well as the radial thrusts and the bearing does not involve thrust washers that are subjected to rapid wear. The cutter bearings are dependable and the balls 44 and 52 cannot become lost or displaced. The bushing sections or bushing parts are dependably locked against loss and displacement and cannot rotate. The bearings are simple and embody a minimum number of parts. The bearings for the outer cutters involve the sectional bushings 43 facilitating the assembling of the cutters and bearing parts. The series of balls cooperating with the interiors of the cutters support the cutters for free rotation with a minimum of friction and wear.

Having described only typical preferred forms and applications of my invention, I do not wish to be limited or restricted to the specific details herein set forth, but wish to reserve to myself any variations or modifications that may appear to those skilled in the art or fall within the scope of the following claims:

Having described my invention, I claim:

1. In a well bit, a supporting pin, a rotatable cutter, an internal ridge in the cutter spaced between its ends, ball races on the opposite sides of the ridge, a sectional bushing on the pin having end flanges overhanging the ends of the cutter, ball races in the bushing opposing the first named races, and series of balls cooperating with the sets of opposing races to rotatably support the cutter.
2. In a well bit, a supporting pin, a rotatable cutter, an internal ridge in the cutter spaced between its ends, ball races on the opposite sides of the ridge, a bushing on the pin, flanges on the bushing engaging the opposite ends of the cutter, ball races in the bushing occurring in the corners between the flanges and the peripheries of the bushings to oppose the races on the ridge, and series of balls cooperating with the sets of opposing races to rotatably support the cutter.
3. In a well bit, a supporting pin, a rotatable

5 cutter, an internal ridge in the cutter spaced between its ends, ball races on the opposite sides of the ridge, a bushing on the pin, flanges on the bushing overlapping the opposite end faces of the cutter, ball races in the bushing occurring in the corners between the flanges and the peripheries of the bushings to oppose the races on the ridge, the bushing comprising two sections each having a flange and a race, and series of balls cooperating with the sets of opposing races to rotatably support the cutter.

4. In a well drilling bit, a supporting pin, a rotatable cutter, rollers rotatably supporting the cutter on the pin, a bushing on the pin entering one end of the cutter and overlapping said end of the cutter to close it, opposing races in the cutter and bushing and balls cooperating with the races, the races being related so that a line passing through the points of contact of a ball with races is pitched relative to the axis of rotation of the cutter whereby the balls assume the end thrusts on the cutter.

5. In a well bit, a supporting pin, a rotatable cutter, an internal ridge on the interior of the cutter spaced between its ends, a ball race on a side of the ridge, a bushing on the pin having an end flange overlapping an end of the cutter, a ball race on the bushing opposing the first named race, and a series of balls cooperating with the said races to rotatably support the cutter.

6. In a well bit, a straight cylindrical supporting pin, a rotatable cutter having internal ball races, a bushing comprising sections slid on the pin to extend into the ends of the cutter, flanges on the bushing sections projecting radially outward to overlap the ends of the cutter, each bushing section having a race opposing a race on the cutter, and balls cooperating with the opposing races to rotatably support the cutter.

7. In a well bit, a straight cylindrical supporting pin, a rotatable cutter having internal ball races, a bushing comprising sections slid on the pin to extend into the ends of the cutter, flanges on the bushing sections projecting radially outward to overlap the ends of the cutter, parts on the cutter overlapping the peripheries of the flanges, each bushing section having a race opposing a race on the cutter, and balls cooperating with the opposing races to rotatably support the cutter.

ALFRED C. CATLAND.
